UNITED STATES PATENT OFFICE.

CHARLES HENRY McDERMOTT, OF EVELETH, MINNESOTA.

RAILWAY-TICKET.

No. 829,797.

Specification of Letters Patent.

Patented Aug. 28, 1906.

Application filed February 24, 1905. Serial No. 247,100.

To all whom it may concern:

Be it known that I, CHARLES HENRY McDERMOTT, a citizen of the United States, residing at Eveleth, in the county of St. Louis 5 and State of Minnesota, have made certain new and useful Improvements in Railway-Tickets, of which the following is a specification.

The object of my invention is to provide an 10 improved round-trip ticket for use on rail-ways, the same being adapted to prevent mistakes and facilitate the work of the conductor in collecting.

The details of the invention are as herein- 15 after stated, and illustrated in the accompa-nying drawing, in which there is represented a face view of a return-trip ticket embodying my invention.

The ticket as a whole is divided trans- 20 versely and lengthwise by lines of perfora-tions, (indicated by *x* and *y*.) Thus the ticket is divided into two parts A A and B B, which are for the most part duplicates of each other, save that in one part A the names of the sta- 25 tions or places from and to which the traveler intends to proceed are interchanged in a well-understood manner. Thus the body part A on the outgoing ticket reads "Jonesville to Smithville," while on the other ticket the 30 names are transposed, as "Smithville to Jonesville." Similarly, on the hat-check B "Smithville" appears on one and "Jones-ville" on the other. Both parts A and B bear the name of the railroad company and simi- 35 larly distinguishing-numerals, in this instance "1420." The hat-check also bears the initials "S," "M," "T," &c., indicating the days of the week, the same being arranged in the same transverse line on the two hat-checks. Be- 40 low these letters are arranged the numerals "1" to "31," inclusive, on each hat-check B, the same being placed in serial numerical order in transverse lines, as shown. At the end of each check B is also indicated a trans- 45 verse row of stars.

When the conductor takes up the ticket, he separates the outgoing and returning portions along the line *y* *y*, and also separates the out-going portion on the line *x* *x*, leaving the hat- 50 check of the outgoing ticket and the entire return-trip in the possession of the pas-senger. The conductor punches the hat-check B of the outgoing ticket to indicate on what day the ticket is seen and taken up by him.

Thus, supposing it be Tuesday, the 9th day of 55 the month, he punches the ticket at *c*, as in-dicated in the drawing. This is done by the first conductor. The next conductor who sees the ticket, if it be on the same day, will punch the star which is in alinement with the 60 letter and date aforesaid. Thus he will punch the star indicated at *b*. The function of the stars is, therefore, to indicate that each con-ductor may punch the hat-check whether it 65 passes through his hands or not on the same or a different day.

The advantages of my improved ticket will be readily perceived. As before stated, each ticket-office, or at least each principal one, will furnish tickets with a differently- 70 colored or differently-marked hat-check por-tion B, so that when passengers get on a train it will be known by the hat-check at what station this occurs, and a special advantage will be obtained in case a passenger should 75 detach the hat-check from the rest of the ticket. The punching of the hat-check at the points indicated will save disputes between conductor and passenger, since the passenger will have a check to show that he had a com- 80 plete ticket, besides the particular date on which the latter was taken up. The provi-sion of the stars at the end of the ticket for indicating a place for punching is particularly 85 advantageous in case the hat-check should pass through the hands of two or more con-ductors on the same date. The hat-check being practically in the form of a calendar is 90 very convenient for passengers going on long journeys, since by consulting the same they 95 may instantly recall or ascertain on what day of the week or month the journey was begun. The same feature of the hat-check also enables it to be used as a stop-over ticket by limit-ing the date by punching and making a notation 95 of the place where the passenger is allowed to stop. In general, this form of ticket will ob-viate mistakes or render them almost impos-sible in checking passengers, and passengers 100 will not be so frequently missed or over-looked, and the conductor can "work" his train in about half the time now ordinarily required.

Having thus described my invention, what I claim as new, and desire to secure by Let- 105 ters Patent, is—

A return-trip railway-ticket composed of two parts of like size and form, each consist-

ing of a "straight" ticket, or body portion, and a hat-check, the four several parts all bearing the name of the railway and the same designating-number, the body portions bearing the names of the stations between which the ticket is available, and the hat-checks bear each the name of one of said stations, and being also distinguished from the straight

ticket by color and having also the initials of the days of the week and the numbers 1 to 31, ¹⁰ inclusive, for the days of a month, arranged *seriatim* across the ticket, as described.
